(57) **CLAIM**

We claim the ornamental design for a control box for charger, as shown and described.

DESCRIPTIONFIG. 1 is a perspective view of front, bottom and right of a control box for charger, showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom view thereof;
FIG. 8 is a front elevational view thereof in a first state of use; and,
FIG. 9 is a perspective view thereof in a second state of use. The broken lines are included for the purpose of illustration only and form no part of the claimed design.**1 Claim, 6 Drawing Sheets****Fig. 1**
